UNITED STATES PATENT OFFICE.

PATRICK J. MURPHY, OF DUBOIS, PENNSYLVANIA.

STEEL MINE-RAIL TIE.

1,389,066.

Specification of Letters Patent. Patented Aug. 30, 1921.

Application filed December 27, 1920. Serial No. 433,193.

To all whom it may concern:

Be it known that I, PATRICK J. MURPHY, a citizen of the United States, residing at Dubois, in the county of Clearfield and

5 State of Pennsylvania, have invented certain new and useful Improvements in Steel Mine-Rail Ties, of which the following is a specification, reference being had therein to the accompanying drawings.

10 The present invention relates to a steel mine rail tie and its object is to provide a tie of this character possessing marked and important advantages over known devices of this nature as hereinafter set forth.

15 In the accompanying drawing:

Figure 1 is a plan view of one end of a mine rail tie, illustrating a part of the rail secured thereon;

Fig. 2 is a cross section of one of the ties;

20 Fig. 3 is a partial side elevation of one of the ties and with one of the rails shown in cross section;

Fig. 4 is an end elevation of one of the ties; and

25 Fig. 5 is a perspective view illustrating a pair of the ties and the rails in assembled relation.

Like numerals designate corresponding parts throughout the several figures of the

30 drawing.

The ties constituting the subject matter of the present invention are of plate like formation and are preferably formed of

35 steel and comprise the body portions 5 having hooks 6 struck therefrom which are adapted to engage over the inner edges of

the base flanges 7 of the rails. The hooks 6 not only take the place of spikes to hold

30 the inner edges of the base flanges of the rails but they serve as gage elements to

properly space the rails 8 and 9 from each other. Oppositely directed hooks 10 and

45 11 are struck from the plate 5 outwardly of the rail and clamping plates 12 are

adapted to lie between and engage beneath

40 the hooks 10 and 11. By referring to Figs. 1 and 5 it will be seen that these clamp plates taper somewhat toward their inner ends and this in conjunction with the fact

50 that the upper face of the base flange of the rail lies at an inclination causes these clamping plates to wedge themselves firmly in position as they are forced inwardly. Outward movement of the clamping plates

55 is prevented by tapering wedge pins 13 which are adapted to be dropped into any

one of a plurality of openings 16. Downwardly directed prongs 17 are struck from the ends of the ties and are adapted to engage in the mine floor to prevent lateral 60 shifting of the track as a whole.

From the foregoing description it will be seen that the tie herein provided is of such nature that the track may be very quickly laid or equally as quickly removed. While

65 I have described the invention as being primarily intended for use in connection with mine car tracks, it will be apparent that it is equally as useful in any relation where it is desired to temporarily lay a

70 track or disassemble the same for the purpose of shifting the position of said track. For example, in lumbering temporary tracks are laid into the woods and it becomes necessary to shift the position of the track as

75 the cutters move from place to place. The tie herein shown and described is useful for this purpose or in any other relation where quick assembly or disassembly of the track is necessary. However this tie pos-

80 sses many features of novelty and advantage which particularly adapt it for use in mines. For example, the body portions of the ties being composed of flat plates of approximately only $\frac{3}{8}$ of an inch in thick-

85 ness effect a considerable difference in the height of the finished track over the old style wooden tie. This is of importance in mines where, frequently, the overhead room is limited when working in low veins of

90 coal. Furthermore, since the track is lower it follows that the height of the mine car, as a whole, will be lower and thus the miner will not have to lift his coal as high when loading mine cars upon this track as

95 would be the case with the old style track.

In laying the rails it is only necessary to place them in position with their base flanges beneath the inner hooks 6 and there-

100 after force the wedge like clamping plates 12 in position and drop the pins 13 in place. There are no lugs to be bent up or down,

105 to become weakened or broken off after being bent up and down a number of times as is the case with some of the forms of ties heretofore proposed.

A further advantage of the structure here-

110 in shown and described is that if a car jumps the track it may be very easily put back on the rails owing to the fact that the first two

wheels of the car cannot drop down between these ties to the extent that they formerly

did between wooden ties. Where the wheels dropped downwardly to a considerable extent between the wooden ties this caused the rear wheels of the car to jump the track and 5 rendered it necessary to unload the car before it could be restored to its position on the rails.

The steel ties herein shown and described can be used indefinitely, where the old 10 wooden ties had to be frequently replaced after spikes had been driven into them a few times.

It is to be understood that the invention is not limited to the precise construction set 15 forth but that it includes within its purview whatever changes fairly come within either the terms or the spirit of the appended claims.

Having described my invention, what I 20 claim is:

1. A metallic tie of the character described comprising as an integral structure a body portion, abutments carried thereby adapted to engage over the inner edges of 25 the base flanges of the rails, hooks struck from the upper face of the tie outwardly of the rail which project toward each other and are spaced above the upper face of the tie, in combination with substantially flat 30 clamping plates adapted to slide beneath said elements and engage over the outer base flange of the rail and means for preventing outward movement of said clamping plates.

2. A structure as recited in claim 1 where- 35 in the means for preventing such outward movement consists of pins which vertically traverse the body portion of the tie.

3. A structure as recited in claim 1 where- 40 in the ties are provided with a plurality of openings formed therethrough and the means for preventing such outward movement of the clamping plates comprise tapered pins adapted to engage in said openings.

4. A tie of the character described com- 45 prising a flat plate like body portion having integral outwardly directed hooks struck therefrom adapted to engage over the inner edges of the base flanges of the rails, spaced hooks projecting at right angles to 50 the first named hooks and struck from said body portion outwardly of the rail, tapered clamping plates adapted to slide beneath the last named hooks and to engage over the base flanges of the rails and tapered pins 55 for engaging the outer edges of the clamping plates, said ties being provided with a plurality of openings some of which lie farther from the rails than others, said tapered pins being adapted to engage in any 60 of said openings.

5. A structure as recited in claim 4 where- 65 in said ties are provided with downwardly directed prongs.

In testimony whereof I hereunto affix my 65 signature.

PATRICK J. MURPHY.
